ATTORNEY.

UNITED STATES PATENT OFFICE

WILLIAM GREEN COLLINS, OF WICHITA FALLS, TEXAS

RADIATOR

Application filed August 17, 1928. Serial No. 300,290.

This invention relates to motor vehicle radiators of that type wherein water from the cylinder jacket is circulated through a plurality of tubes or cores for cooling the water before it is returned to the cylinder jacket.

The primary object of the invention is to provide, in a manner as hereinafter set forth, a radiator of the above mentioned type wherein the water is circulated through a series of such tubes or cores arranged in a manner whereby a maximum surface of the tubes or cores is exposed to the atmosphere for absorbing heat from the water within the tubes or cores through the walls thereof, thereby cooling the water to a maximum degree before the same is returned to the cylinder jacket.

A further object of the invention is to provide a radiator of the type as aforesaid which is simple in construction, positive in operation, efficient in use, and which may be manufactured at sufficiently small cost to make the same practical for installation on motor vehicles of the inexpensive type.

With the foregoing and other objects in view the invention consists in the novel construction, combination and arrangement of parts as hereinafter more particularly described and illustrated in the accompanying drawing wherein for the purpose of illustration is shown an embodiment of my invention, but it is to be understood that changes, variations and modifications may be resorted to without departing from the scope of the claims hereunto appended.

In the drawings in which like numerals are employed to designate like parts throughout the same,

Figure 1 is a front elevation of a radiator constructed in accordance with this invention showing a portion thereof broken away.

Figure 2 is a central, vertical section through my improved radiator as indicated at line 2—2 of Figure 1.

Figure 3 is a transverse section through my improved radiator as indicated at line 3—3 of Figure 1.

Referring in detail to the drawing the numeral 1 indicates generally a radiator shell

formed with a central portion 2 having a pair of side members 3 and having an open front and back. The shell 1 is further formed with an upper water compartment 4 and a lower water compartment 5. The bottom wall 6 of the upper compartment 4 from front to back is formed with an offset portion 7, and from the offset portion 7 an arcuate partition 8 extends to the rear wall 9 thereby dividing the upper compartment 4 into a forward sub-compartment 10 and a rearward sub-compartment 11.

The lower compartment 5 is provided with a vertical partition 12 which extends from the upper wall 13 of the compartment 5 to the lower wall 14 thereof, whereby the lower compartment 5 is divided into a forward sub-compartment 15 and a rearward sub-compartment 16. The sub-compartments 15 and 16 are provided with drain cocks 17 and 18 respectively which open through the bottom wall 14 of the compartment 5.

The central portion 2 of the shell 1 is provided with a plurality of spaced plates 19 which extend horizontally and terminate in the side walls 3. Adjacent the forward edge 20 thereof, each of the plates 19 is provided with a row of perforations 21 through which extend a plurality of tubes or cores 22. The tubes 22 extend through the walls 13 and 6 with the lower ends 23 of the tubes projecting into the sub-compartment 15 and with the upper ends 24 of the tubes projecting into the sub-compartment 10. Spaced from the row of perforations 21 is a similar row of perforations 25 through which extend a plurality of tubes or cores 26 which extend through the walls 13 and 6 with the lower ends 27 of the tubes projecting into the sub-compartment 15 and with the upper ends 28 of the tubes projecting into the sub-compartment 11.

Adjacent the rearward edge 29, each of the plates 19 is formed with a row of perforations 30 through which extend a plurality of tubes 31 which extend through the walls 13 and 6 with the lower ends 32 of the tubes 31 projecting into the sub-compartment 16 and with the upper ends 33 of the tubes 31 projecting into the sub-compartment 11.

The sub-compartment 10 is provided with

a filler neck 34 having a suitable cap 35 for supplying the radiator with water. Having its upper end disposed within the neck 34 is an overflow pipe 36 which extends vertically throughout the height of the radiator with its lower end 37 extending therebelow. Disposed beneath the filler neck 34 is an arcuate baffle plate 38 which extends from the front wall 39 of the compartment 4 to the rear wall 9 thereof. Extending through the partition 8 and baffle plate 38 is a steam escape pipe 40, one end of which is disposed within the sub-compartment 11 and the other end of which is disposed within the filler neck 34 adjacent the inner end of the overflow pipe 36.

15 Leading from the sub-compartment 16 is an outlet pipe 41 for conducting the water from the radiator to the cylinder jacket of a motor, not shown, and opening into the sub-compartment 10 is an inlet pipe 42 for returning the water from the cylinder jacket to the radiator. The pipe 41 is adapted to be provided with a suitable pump of any well known construction for the circulation of water.

25 In the operation of my improved radiator, the water flows from the sub-compartment 10 through the tubes or cores 22 to the lower sub-compartment 15. Due to the forced circulation, the water rises from the lower sub-compartment 15 through the tubes or cores 26 to the upper sub-compartment 11 from which it passes through the tubes or cores 31 to the lower sub-compartment 16 to be returned to the cylinder jacket through the outlet pipe 41. It will be readily seen that the

35 water from the cylinder jacket must traverse the height of the central portion 2 of the radiator three times before it is returned to the cylinder jacket and throughout the passage of the water through the tubes 22, 26 and 31 the heat from the water is driven off through the walls of the tubes to the atmosphere with which the outer surfaces of the tubes are in contact thereby cooling the water

40 to an advanced degree before the same is returned to the outlet pipe 41. Any steam that might be generated in the upper sub-compartment 10 may pass directly through the overflow pipe 36 and any steam which may be generated within the upper sub-compartment 11 may pass through the steam escape pipe 40, thence through the overflow pipe 36.

45 It is to be understood that the form of the invention herewith shown and described is to be taken as the preferred example of the same and that various changes in the size, shape and arrangement of parts may be resorted to without departing from the spirit of the invention or the scope of the appended claims.

50 60 What I claim is:

1. A radiator comprising a shell formed with an upper compartment and a lower compartment, an arcuate partition within the upper compartment to divide the same into

65 a forward sub-compartment and a rearward

sub-compartment, a vertical partition within the lower compartment to divide the same into a forward sub-compartment and a rearward sub-compartment, a plurality of tubes connecting said upper forward sub-compartment with said lower forward sub-compartment, a plurality of tubes connecting each of said lower sub-compartment with said upper rear sub-compartment, said lower rearward sub-compartment being provided with an outlet and said upper forward sub-compartment being provided with an inlet, an overflow pipe for said upper forward sub-compartment, and a steam escape pipe connecting said upper rear sub-compartment and having one end adjacent the inner end of said overflow pipe.

70 75 80 85 90 95 100 105 110 115 120 125 130 2. A radiator comprising a shell formed with an upper compartment and a lower compartment, a partition within the upper compartment to divide the same into a pair of sub-compartment, a partition within the lower compartment to divide the same into a pair of sub-compartment, one of said upper sub-compartment having an overflow pipe and further having a plurality of tubes connecting it with one of said lower sub-compartment, the other of said upper sub-compartment having a steam escape pipe and further having a plurality of tubes connecting it with each of said lower sub-compartment, said upper compartment being provided with an inlet and said lower compartment being provided with an outlet.

In testimony whereof, I affix my signature hereto.

WILLIAM GREEN COLLINS.
